UNITED STATES PATENT OFFICE.

FRANK K. LATHROP, OF DAYTON, OHIO, ASSIGNOR TO THE OHIO RAKE COMPANY, OF SAME PLACE.

DESIGN FOR A SEED-PLATE FOR CORN-PLANTERS.

SPECIFICATION forming part of Design No. 33,561, dated November 13, 1900.

Application filed October 15, 1900. Serial No. 33,174. Term of patent 7 years.

To all whom it may concern:

Be it known that I, FRANK K. LATHROP, a citizen of the United States, residing at Dayton, in the county of Montgomery and State 5 of Ohio, have invented and produced a new and original Design for Seed-Plates for Corn-Planters, of which the following is a specification, reference being had to the accompanying drawings, forming part hereof.

10 Figure 1 is a plan view of a seed-plate for corn-planters, showing my new design. Fig. 2 is a side elevation of the same.

As shown in the drawings, the leading or material feature of my design consists in the 15 arrangement of the seed-openings A in the

plate B in groups of three, so as to form in outline a series of triangular groups around the plate, each seed-opening being also scalloped, as shown, to form four semicircular projections.

Having thus described my invention, what I claim, and desire to secure by Letters Patent, is—

The design for a seed-plate for corn-planters, as herein shown and described.

FRANK K. LATHROP.
